United States Patent Office

Des. 179,684
Patented Feb. 12, 1957

179,684

CONTROL INSTRUMENT

Robert Haven Hose, Mountainside, N. J., assignor to
Minneapolis-Honeywell Regulator Company, Minne-
apolis, Minn., a corporation of Delaware

Application June 6, 1956, Serial No. 41,775

Term of patent 14 years

(Cl. D52—7)

FIG. 1

FIG. 2

FIG. 3

Figure 1 is a front elevation of a control instrument, embodying my new design;

Figure 2 is a top elevation of the device shown in Figure 1, and

Figure 3 is a front perspective view of the device shown in Figure 1.

I claim:

The ornamental design for a control instrument, substantially as shown.
